UNITED STATES PATENT OFFICE.

LOUIS GODDU, OF WINCHESTER, ASSIGNOR TO GEORGE E. FELLOWS AND HENRY S. PAIGE, BOTH OF LAWRENCE, MASSACHUSETTS.

DESIGN FOR AN EMBLEMATIC STAND OR TRIPOD FOR USE BY SECRET SOCIETIES.

SPECIFICATION forming part of Design No. 12,331, dated June 28, 1881.

Application filed May 21, 1881. Term of patent 3½ years. *

To all whom it may concern:

Be it known that I, LOUIS GODDU, of Winchester, county of Middlesex, State of Massachusetts, have invented and produced a new and original Design for an Emblematic Stand or Tripod for Use by Secret Societies, &c., of which the following description, in connection with the accompanying drawings, is a specification.

10 Figures 1 and 2 are elevations from different sides, and Figs. 3 and 4 details showing ornaments on the other sides corresponding to the ornament shown in Fig. 1.

The stand is intended to hold a wand or rod, 15 or it may be employed to hold a vase of flowers or any similar object, as desired.

The three legs *a* of the stand are formed as ogee curves, they widening from their feet to their tops, where the outlines of each pair 20 of adjoining legs unite by a curve, *2*, tangent to both of them, and the legs themselves unite in a continuous dome-shaped portion, *b*, connected by a reverse curve with a tapering standard, *c*, formed as a frustum of a cone and 25 surmounted by an annular beading, *d*. The faces 3 of the legs are curved, so that the entire stand forms a portion of a bell-shaped surface, it having three equal and symmetrical sections removed from between the portions 30 that form the legs. The outline of the legs is defined by beading *e*, extending continuously around the edge of each adjacent pair of legs, the said outline being like an inverted **U**, and symbols *f*, emblematic of the society or order 35 by which the stand is to be used, are drawn or painted in suitable colors upon the dome-shaped portion *b* of the stand at the top of each leg *a*.

When used as a wand-stand, the wand *u* passes down through the standard *c* and rests in a cup, *g*, placed in a saucer, *h*, made in open 40 filigree-work placed between the feet of the said tripod. A gilded ball, *i*, is placed upon one of the feet of the said tripod.

I claim—

1. The hereinbefore-described design for a 45 tripod, consisting of the ogee-curved legs *a*, uniting to form a dome, *b*, connected by a reverse curve with the frustum-shaped standard *c*, the outline of each adjacent pair of the said legs being a continuous curve defined by a 50 beading, *e*, all as shown and described.

2. The tripod-legs *a*, uniting in a dome-shaped surface surmounted by a standard, *c*, formed as a frustum of a cone, and ornamented with emblematic symbols *f*, as shown and described. 55

3. The tripod consisting of ogee-curved legs united in a dome-shaped surface ornamented with the emblematic symbols *f*, and having the ball or sphere *i* upon one of its feet. 60

4. The tripod with ogee-curved legs uniting in a dome-shaped surface surmounted by a standard shaped as the frustum of a cone, and the wand *u*, passing centrally through the said standard, and the cup *g* and saucer *h*, located 65 between the feet of the tripod and receiving the end of the said wand, all as shown.

In testimony whereof I have signed my name to this specification in the presence of two subscribing witnesses.

LOUIS GODDU.
